CARPENTER'S WORK BENCH.
APPLICATION FILED DEC. 6, 1916.

Patented May 14, 1918.

2 SHEETS—SHEET 2.

UNITED STATES PATENT OFFICE.

THEODORE SWANSON, OF LYNN CENTER, ILLINOIS.

CARPENTER'S WORK-BENCH.

1,266,173.

Specification of Letters Patent. Patented May 14, 1918.

Application filed December 6, 1916. Serial No. 135,430.

To all whom it may concern:

Be it known that I, THEODORE SWANSON, residing at Lynn Center, in the county of Henry and State of Illinois, have invented 5 certain new and useful Improvements in Carpenters' Work-Benches, of which the following is a specification.

My present invention is particularly directed to improvements in work benches 10 that are more especially designed for carpenters' uses, and specifically, my invention seeks to provide certain improvements on the work bench construction disclosed in my Patent #1,112,729, dated October 6, 15 1914.

Among other objects, my present invention has for its purpose to provide in a work bench construction, certain elements that may be produced as attachments in the nature 20 of metal parts adapted for being sold as separate articles and which, with certain instructions how to assemble them, are designed to be readily applied to a wooden bench structure that can be readily put up 25 by any carpenter.

In my patented work bench structure, means is provided for feeding a board into position for being planed or dressed and in such means is included a plurality of independently operated feed screw devices.

One of the objects of my present invention is to provide in the metal attachments, means whereby a single actuating crank operates to impart motion to all of the feed 30 devices that adjusts the board to be dressed.

Another feature of my present invention lies in the improved means for mounting the planer whereby it may be readily adjusted for dressing a straight edge or for dressing 40 the edge of the board at the desired angles.

With other objects in view that will hereinafter appear, my present invention embodies the peculiar features of construction, 45 and coöperative arrangement of the parts fully set out in the following description, specifically pointed out in the appended claims and illustrated in the accompanying drawings, in which:

50 Figure 1 is a perspective view of my improved work bench construction.

Fig. 2 is a longitudinal section of my improved work bench.

Fig. 3 is a cross section on the line 3—3 on 55 Fig. 2, the hinged top being swung back to its pendent position.

Fig. 4 is a cross section of the complete bench on the line 4—4 on Fig. 2, and showing a board clamped for planing.

Fig. 5 is a cross section on an enlarged 60 scale of the planing device, and illustrates the means for adjusting the said device at an angle to the board being dressed.

Fig. 6 is a detail perspective view that shows the several metal parts that constitute 65 the board holder or support raising and lowering mechanism.

Fig. 7 is a diagrammatic section that illustrates the means for clamping the board against the hanger member. 70

Figs. 8, 9 and 10 are detail views of parts hereinafter specifically referred to.

In my present construction of work bench, instead of using a number of longitudinal base timbers, as in my patented 75 work bench referred to, a single longitudinal base timber 3 is employed, and the said timber rests upon a series of cross members 4, preferably three, as shown.

The timber 3, at suitable intervals, is 80 bolted to the cross members 4, and in the construction shown, it is located between the series of uprights or posts 2—2, it being of sufficient width to snugly seat, at its opposite edges, against the opposite ones of 85 the sets of posts 2 secured to the timber 3 by long cross bolts and nuts 4a.

40—40 designate bracing irons secured at their upper ends to the uprights 2—2 and at their lower end to the outer ends of the 90 cross members 4—4. Similar bracing irons 40—40 are fastened to the intermediate uprights 2—2 and the corresponding cross members 4—4.

1—1 designates the oppositely disposed 95 guide timbers that form the guideway for the planing implement, hereinafter referred to, and each of the said guide timbers is provided with a pendent adjusting bolt 5, each of which passes through a bracket 50, 100 one of which is mounted on each of the several uprights 2—2 and the said bolts carry adjusting nuts 51 that operate to hold the guides 1—1, the adjustment of which serves to hold the said guides 1—1 105 level.

The vertical guide bars 8—8 in my present construction each have elongated horizontal slots 80 in their upper and lower ends for receiving bolts 81 that adjustably secure 110 the said bars to the uprights 2—2, as is best shown in Figs. 2, 3 and 4.

2
By securing the bars 8 in the manner shown and described they may be readily moved back and forth into the right position to square with the guide rails 1.

5 The longitudinally extended bar in the present showing of my invention is located between the opposite sets of the uprights 2-2 and it forms a supporting member upon which the board, whose edges are to 10 be planed or beveled, is edgewise supported, and the said bar at each end has a laterally projected bracket 11-11, and each of the brackets has a threaded vertical aperture 12 for receiving the vertically positioned adjusting screw shafts 13-13 on 15 the lower end of each of which is secured a bevel gear 43, and the said lower ends of the said shafts 13-13 are journaled in bearing brackets 14-14^a. Gears 43 mesh with 20 bevel gears 42-42 on a horizontally disposed operating shaft 41, one end of which extends beyond one end of the bench and carries a bevel gear 44 that is held in mesh with a like gear 45 on a vertically extended 25 crank equipped shaft 45^a, as is clearly shown in Fig. 1.

In my patented bench structure before referred to, each screw shaft 13 is provided with a separate crank operated power 30 mechanism. In my present invention I have provided for operating the several shafts 13 simultaneously and under a single crank actuated means and to such end each of the brackets 14-14^a includes a right 35 angled pendent portion 14^b apertured to form the bearings for a horizontal shaft 41 which extends lengthwise of the machine and carries a pair of beveled gears 42-42 that mesh with pinions 43-43 on the lower 40 ends of the screw shafts 13-13.

44 designates a pinion mounted on the outer end of the horizontal shaft 41 which meshes with a pinion 45 on a shaft 45^a mounted at one end of the machine and 45 which is provided with an operating crank, as is shown in Fig. 1.

Instead of providing a planer having side flanges, as indicated by 33 in my patent referred to, I have provided an improved 50 means for dressing the upper edge of the board, and the said means, which is best illustrated in Figs. 4 and 5 of the drawings, comprises a planer, the blade 47 of which is mounted in the planer body in any improved 55 manner.

49 denotes a side member pendent from the cross or hanger bar 58, the latter being of sufficient length to straddle and ride upon the upper edges of the side guides 60 1-1.

At one side, the planer body is hingedly connected as at 48, to the member 49, as is best shown in Fig. 5, by reference to which it will be also seen that the hanger bar 58, where it passes across the planer, is

formed with a forwardly bent portion 58^a whereby to provide ample space for the ready rise and escape of the shavings during the operation of planing.

At that side opposite the hinged connection of the planer, the bar 58 is provided with a slot 60 for the passage of a curved extension 59 secured to the planer body, the adjusting of which, up and down through the side slot 60, provides for setting the 75 planer in a plane with the edge of the board to be trimmed or at an angle to the said edge, whereby to dress the edge of the board being worked with a bevel trim as desired. 80

In my present construction of attachments for carpenter's work bench, such as is shown in my patent before referred to, instead of using independently adjustable upper and lower clamp members for holding the board 85 to be dressed against the guide members 8, I employ a single clamping mechanism that can be quickly adjusted for applying the desired sidewise clamping of the board being operated on, and the said mechanism, best 90 shown in Figs. 3 and 7 includes a number of U-shaped pivot rods 64, one member of each of which is pivotally connected with the inner edge of the respective standards 2 at the front side of the bench, while the other member of each of such rods 64 pivotally connects to a laterally shiftable presser or 95 clamping member 63 that extends lengthwise of the bench and is located above the brackets 11, as is clearly shown in Figs. 3 100 and 4.

The hand hold 65 is attached to the presser member 63 for pulling the said member in the direction of its length to cause such member, by reason of the link connection 64 105 with the uprights 2-2 to swing inwardly tightly against the board 10 to be worked on (see Fig. 4) and thereby hold the said board up against the guide members 8.

For holding the presser member 63 110 clamped up against the board, the said member 63 has a ratchet surface 90 that is engaged by a resilient stop pawl 91, as is indicated in Figs. 6 and 7.

In my present construction, the bench board 28 has hinged members 30 attached to and extended entirely across the bottom of the board and connected, at one end, to hinged members 31 on the adjacent or inner side member 31^a of the bench, the latter and 120 the outer side member having grooves 31^b-31^c in the upper edge thereof as indicated on Fig. 1 and, as in my patented work bench referred to, the board 28 is so hinged that when swung back, it hangs flatwise over one 125 side of the bench (see Figs. 3, 4 and 5).

At the head end, the board 28 has two longitudinally extended strap iron members 52-52 and they are attached to the board by screws 52^a-52^b and the outer ends of the 130

said members 52 are angled as at 52^b to extend over and hold the cross or bit block 29 securely against the said head end of the board with its bit edge 29^a projected for being engaged by the end of the flat board, as it is held upon the table during the operation of planing the flat side thereof.

Bit block 29 is preferably of metal and it is riveted or otherwise made fast to the 10 strap iron members 52—52.

From the foregoing description taken in connection with the drawings, the complete construction, the manner in which the several parts are operatively assembled and the 15 advantages of the construction of my present invention will be readily understood by those skilled in the art to which my said invention relates.

By reason of constructing the operative 20 parts in the nature of metal attachments and forming them for being coöperatively combined, as shown, the said attachments may be sold independent of the bench structure and readily operatively applied by a carpenter in building the wooden bench structure such as is generally disclosed in the drawings, under printed instructions.

The structural arrangement of the several attachments are such that they may be 30 manufactured at such low cost that when applied to the wooden bench or body structure, an effective and desirable work bench is developed at a small expense of material and time.

35 What I claim is:

1. In a work bench of the character described; the combination of a framing that includes a plurality of oppositely disposed uprights, a horizontal guide member on the

upper ends of each of the said oppositely disposed uprights, means for supporting the board to be placed edgewise between the said guide members, the said means including relatively fixedly held guide members and a longitudinally disposed bar that forms 45 a rest for the board to be planed, mechanism for clamping the board to be planed against the vertical guide members, the said mechanism including a clamping bar pivotally connected to the uprights at one side and 50 adapted for being swung over and held clamped against the board during the operation of planing the upper edge thereof, and further means for effecting vertical adjustment of the bar upon which the board is 55 supported.

2. As an improvement in work benches of the character described in which is included a pair of longitudinally extended guides that form a runway for a planing implement, means for supporting a board for being projected edgewise between the guides, crank operated power transmission coöperatively connected with the board supporting means for intermittently moving the said 60 means to lift the board up between the guides and other means for holding the board from lateral displacement during the operation of planing the upper edge thereof, the said means including vertical side guides 70 laterally adjustable with respect to the board and engaging one face of the board and a longitudinally disposed presser bar that engages the other side of the board and devices for holding the bar to its adjusted 75 position.

THEODORE SWANSON.
